CONRAD ROBERT BUCHET, OF LONG BEACH, CALIFORNIA, ASSIGNOR, BY MESNE ASSIGNMENTS, TO ALEMITE CORPORATION, OF CHICAGO, ILLINOIS, A CORPORATION OF DELAWARE

GREASE GUN

Application filed May 31, 1928. Serial No. 281,925.

This invention relates to a grease gun of a character suitable to inject lubricating grease under pressure into cavities, chambers, bearings and like places. It appertains 5 more particularly to a gun wherein the pressure under which the lubricant is ejected is obtained by the action of a fluid actuated motor. The present invention is adapted to be connected to a source of supply, such as a 10 compression tank and to boost the ejection pressure of the grease, or to have attached thereto a grease supply receptacle forming with the gun a unit.

The objects of this invention are to provide 15 a grease gun of the character described having any or all of the following features: a valve for the control of actuating fluid which normally places the motor member in communication with the exhaust and is operable 20 to connect the motor to a source of supply of actuating fluid under pressure; a reciprocable plunger valve and operating trigger therefor; a casing having a grease ejector barrel, a motor, and means for interchangeably connecting the casing to various types 25 of grease supply chambers; a grease supply chamber detachably mounted on the casing and supplying grease to the ejector barrel under pressure; a grease supply chamber 30 having a floating displacement piston operable to force grease therefrom and actuated indirectly by the fluid actuating the motor; a casing having an ejector barrel, a motor cylinder and a handle for manipulation thereof, 35 which handle is associated with a valve operating trigger; and a grease gun of the character described having the grease moved by influence of three stages of pressure obtained by an actuating fluid.

40 These objects are obtained by means of the embodiment of my invention illustrated in the accompanying drawings in which:—

Fig. 1 is an elevation partly in section of a grease gun having a supply chamber member partly attached thereto adapted to be connected to a compression tank as shown in Fig. 5; Fig. 2 is a section through the grease gun having a supply chamber member attached thereto and forming a complete unit; 45 Fig. 3 is a section as seen on the line 3—3 of

Fig. 2 on an enlarged scale; Fig. 4 is a bottom view as seen on the line 4—4 of Fig. 2; and Fig. 5 is a view showing the unit associated with a compression tank.

Referring more particularly to the drawings, the grease gun comprises a casing having an ejector barrel 6, the bore of the barrel ending in a nozzle 7 adapted to have a hose or any approved type of coupling attached thereto. The casing has a motor cylinder 8 formed thereon in alinement with the ejector barrel and having a bore of much greater diameter than the bore of the ejector barrel. The barrel portion has an extension 9 through which the bore of the ejector barrel extends. 55 Threaded onto the end of the casing so as to close the cylinder barrel is a head 10 having a laterally projecting handle 11 provided with finger grips. On one side of the casing is an annular extension 12 internally threaded to serve for attachment of a supply chamber. Hinged to the handle so as to overlie the latter is a trigger 13.

Slidably mounted in the bore of the plunger barrel is a plunger 14 having at its outer end a piston 15. Bearing against the rear of the piston 15 is a compression spring 16 urging the piston and plunger into their initial ejecting positions. Extending through the casing and communicating with the bore of the ejector barrel is a passage 17 serving for the supply of grease from the supply chamber to the ejector and providing a port which is traversed by the plunger 14 on its displacement stroke. In the casing and communicating with the motor cylinder to the rear of piston 15 is a relief passage 18 controlled by a check valve 19 so as to permit the entrance of air and prevent discharge therefrom. A passage 20 also communicates with the motor cylinder and opens through a boss 21 internally threaded and disposed within the annular extension. A check valve 22 prevents inflow of air into the piston cylinder. 95

The handle 11 has a main passage 23 communicating with the motor cylinder on the front side of piston 15. This main passage connects with a valve chamber 24 extending transversely through the handle and en- 100

larged at the inner end. The enlarged portion is internally threaded to receive a closure plug 25. Extending through the handle is an inlet passage 26 communicating with the valve chamber and internally threaded to adapt it for connection to an air hose or like supply line for fluid under pressure. A plunger valve 27 is mounted in the valve chamber, it having peripherally located passages so that air may travel longitudinally of the valve plunger. At the outer end of the plunger is a head 28 provided with a seat to co-operate with a like seat on the handle to close the port opening to the atmosphere, when the head is seated against the handle. On the other end of the plunger is an enlargement 29 having a seat to co-operate with a corresponding seat to control the flow of air between the inlet passage 26 and the main passage 23. A socket is formed in the opposing ends of the valve plunger and the closure plug 25, and mounted therein is a compression spring 30 tending to hold the plunger valve in its outer position with communication between inlet ports 26 and the main passage 23 closed. The head of the plunger underlies the trigger 13.

Referring more particularly to Fig. 1, a supply chamber member 31 is shown attached to the extension. This member has a coupling extension 32 adapted to be connected to a supply hose. For convenience in operation, there is an extension 33 internally threaded to receive the stem 34 of a screw valve 35 adapted to be seated and to close inlet 17. A handle 36 serves for convenient operation of this valve.

Referring more particularly to Fig. 5, the gun is shown connected to a compression tank 37. This tank is adapted to hold grease of the character which is introduced into automobile differential casings and transmission cases. The inlet passage in the handle is connected by an air hose 38 to a three-way valve 39, one branch of which is connected to the tank 37 to supply pressure thereto, and the other branch of which is connected by a hose 40 leading to a source of air under pressure. The coupling 32 is connected by a hose 41 to the discharge of a fluid meter 42 which measures the grease discharged from the tank 37. A pressure gage 43 is shown on the tank.

During inoperation of the system shown in Fig. 5, valve 35 is maintained closed so that grease will not pass from the tank to the ejector barrel and be wasted therefrom. When it is desired to dispense grease, the valve 35 is opened by turning the handle 36. The valve 39 on the tank is then opened, and air supplied through the hose 40. In the event that the pressure is sufficient, grease will then flow through the discharge nozzle. However, if the back pressure against which the grease is to be discharged is greater than

that which would create a flow, the trigger 13 is depressed to move the plunger valve inwardly and close the main passage 23 to the atmosphere. Movement of the plunger valve to a position closing communication with the atmosphere, opens communication between the inlet passage 26 and the main passage, and air is supplied to the motor cylinder in front of piston 15, causing the piston to be moved against the action of spring 16 and forcing the plunger 14 into the ejector barrel so that it overrides the grease inlet port 17 and closes the latter. In its continued travel, the pressure upon the grease in the ejector barrel is boosted. During the working stroke of piston 15, the check valve 19 closes the relief port and air will pass through the port 20 to the supply chamber. When the piston has reached the end of its working stroke, the trigger 13 is released, and spring 30 causes the plunger valve to be moved connecting the motor cylinder with the atmosphere and shutting off connection with the inlet passage 26. The spring 16 will then return the piston and plunger to their initial positions for another cycle of operation. Upon the return of the piston 15, the relief valve 19 opens to admit air in back of the piston.

Referring more particularly to Fig. 2, a supply chamber cylinder 44 is connected to the annular extension, it being substituted for the member 31 heretofore described. Mounted upon the lower end of the cylinder 44 is a head 45 secured to the cylinder by threads. At the center of the head is an opening 46 which extends through a boss 47. Slidably mounted in the opening 46 is a tubular rod 48, the upper end of which is threaded into the boss 21. At the lower end of the rod are openings 49, and secured to the rod on the outer side of the head is a collar 50 which is adapted to fit snugly against the boss 47 and form a seal therewith. A handle 51 is secured to the end of the rod, the latter being closed thereby. On the upper end of the rod are lugs 52. Slidably mounted in the rod is a floating piston 53.

The structure just described is used in the following manner: the handle 11 is connected to an air hose. The handle 51 is turned to detach the rod 48 from the boss. The cylinder 44 is detached, and the open end plunged into a supply of grease. The handle 51 is then pulled outwardly to draw a charge of grease into the supply chamber, the piston being moved toward the head 45. The cylinder 44 with its charge is again attached to the casing, the rod 48 pushed inwardly and attached to the boss 21.

The handle 51 is screwed up tight, so that the collar 50 seals the space at the rod, and the gun is now ready for introduction of grease to the ejector barrel. Trigger 13 is depressed to admit air in front of the piston 15,

the latter being advanced and forcing air in back of it through the passage 20, rod 48 and openings 49 below the piston 53 which is urged upwardly and forces grease toward the port 17. Check valve 22 prevents the air injected into the cylinder 44 below the piston from returning, upon release of the trigger 13. Upon another operation by depression of the trigger 13, the grease which has entered 10 the ejector barrel will be forced outwardly through the nozzle.

What I claim is:—

1. A grease gun having a casing comprising a grease barrel and a motor cylinder, an ejection nozzle for said barrel, an inlet for supply of grease to said barrel, an extension on said casing in communication with said inlet, a plunger in said barrel; a motor cylinder, a piston therein for actuating said 20 plunger, a main passage for actuating fluid communicating with said cylinder, an exhaust passage and an inlet passage connected to said main passage at a common juncture formed with a valve chamber; a valve in said

25 valve chamber movable to place said main passage either in communication with said inlet passage or said exhaust passage, means to operate said valve; a supply chamber detachably connected to said extension, a detachable head on said chamber, a tubular rod slidably mounted in said head and detachably connected to said casing, a passage in said casing placing the motor cylinder in communication with said rod and in communication with the outer end of said chamber, and a floating piston on said rod for urging grease from said supply chamber through said inlet.

2. The combination in a grease gun of a 40 cylindrical housing having an enlarged chamber therein open at one end, a closure member therefor comprising a combined handle and valve housing, a cup leather piston in said chamber, a plunger projecting therefrom and extending into a bore in said housing a grease reservoir attached to said housing, a pair of spring-pressed ball valves mounted in said housing closing air passageways, one of said passageways extending to 45 atmosphere and the other communicating with the rear end of the grease reservoir, a passageway in the housing connecting the grease reservoir and the bore in said housing, a source of air under pressure connected with 50 said valve housing, a normally closed valve in said valve housing and means for opening said valve to allow air to enter the housing chamber to force the plunger forward ejecting lubricant and simultaneously forcing air from the housing chamber to the rear of the lubricant reservoir.

3. The combination in a grease gun of a cylindrical housing having an enlarged chamber therein open at one end, a combined valve housing and handle unit ar-

ranged to close the end of said chamber, a reciprocable piston in said chamber, a plunger projecting therefrom and extending into a bore in said housing, an inlet for a supply of grease to said bore, a grease reservoir attached to said housing, a pair of one-way valves mounted in said housing closing air passageways, an inlet passage extending to atmosphere and an outlet passage communicating with the rear end of the grease reservoir, a source of air under pressure connected to said combined handle and valve housing unit, a normally closed valve in said unit and trigger means attached to said unit for opening said valve to allow air to enter 70 the housing chamber to force the plunger forward to eject lubricant and simultaneously force air from the housing chamber to the rear of the lubricant in the reservoir.

In witness that I claim the foregoing I have 85 hereunto subscribed my name this 24th day of May, 1928.
